DISTRIBUTOR NOZZLE PLATE

Arthur Fort Stephens, Beaumont, Tex., assignor
of forty-nine per cent to James F. Holt,
Houston, Tex.

Application December 14, 1945, Serial No. 634,909

3 Claims. (Cl. 299—120)

1

The invention relates to a distributor plate for an atomizing nozzle which is capable of a wide range of uses and is particularly adapted for atomizing or spraying fire fighting fluids.

In distributing a liquid, it is often desirable that a maximum area be covered with the fine spray or atomized liquid.

With most types of spray nozzles and particularly nozzles of the adjustable needle type, the spray thrown is usually in the form of a cone, leaving an open or hollow central portion where little or no spray strikes the article.

It is one of the objects of the present invention to provide a distributor for a nozzle wherein the spray is distributed in the form of a solid cone, where the spray is uniformly distributed throughout the cone, including all of the central portion and the periphery as well.

Another object of the invention is to provide a distributor plate for an atomizing nozzle for fire fighting equipment wherein the distributor plate is utilized to break up the solid stream of liquid entering the nozzle so that as it passes through the outlet orifice, it is broken into a fine spray which will be uniformly distributed.

Another object of the invention is to break up the column of liquid prior to its entering the outlet orifice of the nozzle so as to obtain a uniform distribution of the spray.

Still another object of the invention is to provide a distributor plate having two or more slits therein which intersect substantially at the center of the plate surface to form four or more slit radii and to divide the central plate surface into four or more tongue areas.

It is a further object of this invention to provide a distributor plate of this class in which the spray pattern is obtained by pressing the material along an edge of a tongue area out of the plane of the plate in one direction, and by curving the material along the adjacent or intersecting edge out of the plane of the plate in the opposite direction.

Still another object of the invention is to provide a distributor plate having a plurality of slits arranged therein for distributing the liquid passing therethrough.

Other and further objects of the invention will be readily apparent when the following description is considered in connection with the accompanying drawings, wherein—

Figure 1 is a side elevation of a nozzle construction showing the distributor, part in section, in position therein.

2

Fig. 2 is a perspective view of a distributor plate.

Figure 3 is a sectional view of the distributor plate taken along line 3—3 of Figure 2.

In Fig. 1 the nozzle construction embodies a fitting 2 threaded at 3 for connection to a pipe or hose to supply the liquid which is to be distributed. A gasket 4 may form a seal with the end of the pipe or hose and the fitting 2 is rotatable over the flange 5 formed over the end of the conduit 6.

A valve 7 is connected in the conduit 6 and may be of any desired type but a plug 7 rotatable by means of the handle 8 has been shown.

Where the invention is to be utilized as a distributor for fire fighting materials the pipe 6 may be of considerable length so that the operator may stand some distance from the spray, but of course the nozzle may be applied to any other type of conduit. The pipe 6 is shown at 9 as having been bent to an angle. The conduit is threaded at 10 to receive the head 11. This head is made up of the fitting 12 which is engaged as at 13 to provide a chamber 14. A cap 15 is threaded at 16 onto the nipple and serves to clamp the gasket 17, the distributor plate 18, and the retainer ring 19 in position.

This cap has the outlet or orifice 20 disposed therein which serves to discharge the fluid which is being sprayed.

It is desirable as indicated above to obtain a spray which forms a solid cone of atomized material. With the usual type of spray nozzle the liquid approaches the orifice such as 20 as a solid stream and as a general rule results in a cone of spray which is hollow and does not apply a spray to the entire area enclosed by the cone. With the present construction, however, the distributor plate 18 is provided in order to break up the column of liquid entering the chamber 14 and as seen in Fig. 2 this plate or disk 18 has been provided with a slit 22 crossing the medial portion of the disk and the second slit 23 which intersects the first slit. These two slits 22 and 23 divide the central portion of the plate into the areas of a plurality of tongues or tongue portions 25, four in this case. Also, the intersection of the slits divides each slit into two slit radii 29 extending diametrically opposite each other from the plate center. These tongues have been bent in a peculiar manner in that, for instance, with any particular tongue 25 the edge 26 thereof has been bent downwardly, with respect to Figure 1, from the plate while the adjacent tongue edge 27 has been bent upwardly of the plate; in other

words, the tongue has been warped in such a manner that one edge of the tongue extends on one side of the plate while the adjacent edge extends on the opposite side of the plate with the point or apex 28 of the tongue being approximately in the plane of the plate. It is appreciated that it is rather difficult to visualize such a structure but it is believed Fig. 2 illustrates the arrangement by showing that the edge 27 is a straight edge on the inside of the plate while the edge 26 is a curved edge on the outside of the plate.

In other words, the tongue is formed as a segment of a cone so that the area 30 thereof forms a passage for liquid which will tend to throw the liquid out of the plane of the plate 18 and tend to discharge it laterally therefrom.

As seen in Fig. 2 there are four of these tongues 25, all of which are identically and symmetrically formed.

To avoid confusion, it is pointed out that the position of the plate 18 shown in Fig. 3 is the reverse of the position which it occupies in the nozzle as shown in Fig. 1. Consequently it should be noted that the use of the terms "upwardly" and "downwardly" hereinbefore are relative applications of the terms to the position of the plate in Fig. 1.

This plate as seen in Fig. 1 is clamped between the gasket 17 and the spacer ring 19. It will be seen therefore that the liquid being discharged against the inside of the partition 32 of the cap 15 will be given a swirling motion as it approaches the orifice 20.

As the direction of the streams from the several openings 30 thus converge on the orifice 20, the direction thereof has been changed and it is found that the spray from the opening 20 constitutes a cone or column of spray. In actual operation the nozzle has been very effective in distributing fire fighting material.

It is believed that the operation of the nozzle and the distribution of the spray liquid when equipped with the distributor plate of this invention will be readily apparent.

What is claimed is:

1. A distribution plate for sprays comprising a

metal plate, two intersecting slits forming four projecting tongues of material, each tongue being twisted out of the plane of the plate so that one edge projects inwardly and one edge projects outwardly and the tongue curved thereby so that adjacent edges of adjacent tongues form a distribution orifice.

2. A distributor plate for spray nozzles comprising a plate, slits intersecting centrally thereof so that two radially adjacent and centrally intersecting slit radii define a tongue area there-inbetween, one edge of each tongue being curved along a slit radii and out of the plane of the plate in one direction and the other edge along an adjacent slit radii of the tongue being pressed out of the plane of the plate in the other direction, the apex of the cone section thus formed remaining proximate the plane of the plate.

3. A distributor plate for spray nozzles comprising a plate, slits intersecting centrally thereof so that two radially adjacent and centrally intersecting slit radii define a tongue area there-inbetween, each tongue being warped in the form of a cone segment with one edge curved along a slit radii and out of the plane of the plate in one direction as the cone segment base to provide a discharge opening, the other edge along an adjacent slit radii being straight and pressed along a slit radii out of the plane of the plate in the other direction so that the discharge from the opening is deflected away from the plane of the plate.

ARTHUR FORT STEPHENS.
